INTERCOMMUNICATION SYSTEM

Frank Pedatella, New Kensington, Pa.

Application May 26, 1950, Serial No. 164,336

20 Claims. (Cl. 179—37)

1

This invention relates generally to communication systems, and more particularly to such systems embodying a plurality of transducer stations which may be selectively connected together.

This invention, while primarily adapted for, and illustrated in connection with, a direct wire type of intercommunication system, embodies certain fundamental aspects which are useable in other types of circuits. However, it will be appreciated that in the illustrated system, representing a preferred embodiment of the invention, a degree of simplicity is achieved which is not to be found in more conventional apparatus for the intended purpose.

In the usual intercommunication system each master station is provided with equipment including an amplifier, a transducer, usually in the form of a permanent magnet speaker, or, alternatively, a separate speaker and microphone, together with a push button station, the push button station being operated selectively to connect the corresponding master station with other master or staff stations forming a part of the system. Suitable relay switching means under the control of the respective master station push buttons establish the desired circuit connections.

Each master station with its amplifying and switching units represents a complicated and expensive piece of equipment. As a consequence, in installations embodying such equipment, the master station installations are limited to those points from which control and direction of operation is to reside, while the remaining stations, usually referred to as staff stations, are equipped only with a transducer unit completely under the control of the master stations.

In numerous instances, situations arise at the various staff stations which require contact with personnel at one or more master stations, but with such a system the staff personnel has no means through the intercommunication system for contacting the desired master station personnel. This, of course, is a limitation which restricts the effectiveness of the system.

Accordingly, one object of this invention is to provide an intercommunication system of simplified and economical structure, a system which may be installed easily and operated readily—a system which is positive in operation.

Another object of this invention is to provide an intercommunication system in which a central amplification system is employed.

It is also an object of this invention to provide a system of the character referred to, whose

2

stations have but a few operating components, wherein each station functions as a master station.

An ancillary object of this invention is to provide an intercommunication system having simple switch circuits.

The foregoing statements are merely illustrative of the various aims and objects of this invention. Other objects and advantages will be apparent in the following disclosure, when considered in conjunction with the accompanying drawing in which the single figure thereof diagrammatically illustrates a preferred embodiment of the invention.

15 While it will be appreciated that the intercommunication system illustrated in the drawing may incorporate any number of stations, four stations are illustrated in this case, since the structure of the invention and its operation may be fully understood with such showing. The four stations are shown respectively designated S1, S2, S3 and S4. Each includes a transducer element illustrated in block diagram and identified by the reference characters T1 through T4, respectively. 20 Each transducer embodies conventional equipment. For example, the transducer may consist of a standard permanent magnet speaker which may be utilized to convert electrical signals to sound, and, conversely, may be utilized to convert sound or speech to electrical signals. Alternatively, of course, a transducer in each case may include a separate speaker and a separate microphone suitably connected into the system for the intended purpose. Other arrangements 25 may be incorporated for accomplishing the intended purposes, by means of other forms of conventional apparatus.

Each station also includes a plurality of switches, one switch for each station. In station 30 S1 these switches are designated S11 through S14. In station S2 the switches are designated S21 through S24. In station S3 the switches are designated S31 through S34, and in station S4 the switches are designated S41 through S44.

35 Selective switching for interconnecting the desired transducer elements is accomplished by a pair of switch assemblies MSS and SS. Switch assembly MSS is a master station selector switch, and switch assembly SS is an auxiliary selector switch which works in conjunction with the master selector switch MSS to provide connections between the desired transducers. Both switch assemblies are motor operated, switch MSS being driven by a motor 1M and switch SS being driven by a motor 2M.

Referring particularly to the master switch arrangement, the master switch includes four separate switching units, one for each switch station. These separate units are shown as interconnected mechanically operated switch stacks, having an operating member which rides on the surface of a cam 10. This cam is circular in configuration and has a single projection 11 thereon, which during cam rotation successively engages the operating members of the separate switch stacks, and thereby operates these separate stacks. The cam is shown to be mechanically connected to the motor 1M, and this connection is to be understood to include a reduction gear assembly, if required. Control of the motor 1M, which operates the separate switch units, is obtained by suitable interlocking of the motor circuit with normally closed switches 1M1 through 1M4 which are disposed on the respective switch units. These separate switch units have a common terminal connected to one terminal of the motor 1M, the other terminal of the motor 1M being connected to the line 2 of the power supply lines 1 and 2. These supply alternating current (although the apparatus may be designed for direct current) for operating the system. A normal 110 volt A. C. power supply will do.

Each of the switch units of the respective switch stations is illustrated as a three terminal switch. Refer, for example, to the switch S11. This switch includes the terminals or contacts 11a, 11b and 11c which are straddled by a movable contact member which is push-button operated, and which in its closed position, under manually applied pressure, engages all three of the named contacts. The middle contact, 11b, of switch S11 is connected to the power supply conductor 1, and similarly the middle contact of each of the remaining switches of all of the stations is also connected with the power supply conductor 1. Thus, in effect, there are provided with the three terminals, two switches which are simultaneously closed at the time the push-button is operated.

Control of the motor 1M is obtained from the respective stations S1—S4, by connecting certain switch terminals thereof to corresponding terminals of the respective switches designated 1M1 through 1M4. For example, the terminals 11a, 12a, 13a and 14a of station S1 are connected in parallel by means of a common conductor to one of the two contacts of the switch 1M1. The corresponding terminals of switches S21 through S24 of the station S2 are connected in parallel to one contact of switch 1M2; the corresponding terminals of the switches S31 through S34 of station S3 are connected in parallel to one contact of switch 1M3; and the corresponding terminals of the switches S41 through S44 of station S4 are connected in parallel to one contact of switch 1M4. The remaining contact of each of switches 1M1 to 1M4 are connected in parallel to one terminal of the motor 1M, as shown.

Returning to the switch S11 of station S1, it will be appreciated that by depressing the push button of this switch a circuit is completed from the conductor 1 through the contact 11b and contact 11a to one contact of the switch 1M1. Assuming that the cam 10 is in a position different from that illustrated, it will be understood that the contact 1M1 will be in circuit-closing position. Thus, both contacts of the switch 1M1 will be electrically united, whereby electric supply line 1 is connected to one terminal of the motor 1M. The other terminal of motor 1M is perma-

nently connected to the electric supply line 2. Thus, the energizing circuit for the motor is completed.

The motor 1M rotates in one direction only, which in this case is clockwise as viewed in the drawing. It will be understood that the cam 10 will be rotated until the projection 11 thereof engages the operator of the switch stack including the contact arm of switch 1M1. At this point the switch 1M1 is opened and the energizing circuit for the motor 1M is interrupted and the motor stops. The operation involving the control of the motor 1M for the remaining switches S12 through S14 on station S1 is the same, since closure of any one of these switches establishes an energizing circuit for the motor through the contacts of switch 1M1. Thus, regardless of which of the motor operating contacts on station S1 is manually operated, the motor will always stop with the cam in the position illustrated in the drawings.

This same type of operation is effected from any of the remaining switch stations. For example, referring to station S4, the closing of switch S41 completes an energizing circuit for the motor 1M, the circuit running from the conductor 1 through the contact 41b to the contact 41a, and from the latter contact through the two contacts of the closed switch 1M4 to one terminal of the motor 1M, the circuit being completed from the other terminal of the motor 1M to the conductor 2. Assuming that at the time this energizing circuit is completed the cam 10 is in the position illustrated, the motor 1M will rotate the cam clockwise, until projection 11 thereof engages the operator of the switch stack including the switch 1M4. At this time the contact 1M4 is opened and the energizing circuit for the motor is broken.

From the foregoing it will be appreciated that operation of any one of the push buttons hereinabove considered in the respective stations S1—S4 will cause operation of the motor 1M to actuate the switch unit corresponding to the station on which the particular push button switch has been operated, thereby effecting selective operation of the switch units of the master switch MMS.

As earlier noted herein, the auxiliary selector switch SS is operated by a motor 2M. The motor 2M is controlled by a switch arrangement corresponding to the switch arrangement 1M1 through 1M4 of the master switch. This switch arrangement, which is hereinafter referred to as an auxiliary control switch, is generally designated ACS, comprises individual switches 2M1 through 2M4 which are operated by a circular cam 20 having a single projection thereon. The contacts of switches 2M1—2M4 are normally closed except when operated by the cam 20, and these respective switches correspond to the correspondingly numbered switches of the respective stations S1—S4 as identified by the last digit of the respective reference characters. Thus, for example, switches S13, S23, S33 and 2M3 are corresponding switches. Switch S33 is omitted since it is the master switch on station S3. Similarly, switches S11, S22 and S44 are the master switches of the corresponding switch stations S1, S2 and S4. These last named switches are each connected in series with auxiliary control switch 2MA. Switch 2MA, which also is normally closed, represents the position in which the selector switch SS is to be stopped for the purpose of connecting a given transducer with all of the other transducers of the system. This will be more fully described hereinafter.

As the various switches above considered are identified on the respective switch stations, the last digit of the reference character indicates the particular station with which that particular switch is related. For instance, referring to the switch S11, the last digit "1" indicates that such switch is in station 1, and by further examination, with regard to the switch S13, the last digit "3" indicates that by depressing this switch the transducer T1 may be connected with the transducer T3.

In the system herein illustrated the switch which is numbered in accordance with the number of the switch station in which it is located is utilized to connect the transducer of that station with all of the other transducers, by the control afforded through the contact 2MA of the auxiliary control switch ACS, thereby controlling the motor 2M in such a way as to position the selector switch SS to establish connection of the remaining transducers. For example, by closing switch S11 transducers T2 through T4 will be connected with the transducer T1. In a similar manner on station S2 the push button switch S22 is connected with the contacts 2MA to effect connection of the transducer T2 with all other transducers T1, T3 and T4, while either the switches S33, and S44 of the stations S3 and S4, respectively, function in a similar capacity to connect the corresponding transducers with all the other transducers of the system.

In accomplishing this function the contacts 11c, 22c, 33c, and 44c, respectively, of the switches S11, S22, S33 and S44 are connected to one contact of the switch 2MA, the other contact of which switch 2MA is connected in common with all of the corresponding contacts of the switches 2M1 through 2M4 with one terminal of the motor 2M. The other terminal of motor 2M is connected to the conductor 2. As in the case of the set of switches which control motor 1M, each of the switches S11—S44 now being considered in the respective stations S1—S4 is supplied with power from the conductor 1 through each of centrally located contacts thereof (such as the contact 11b of switch S11 of station S1). The remaining switches of each of the stations S1—S4 are utilized as earlier mentioned, to connect the transducer of that particular station with a correspondingly numbered transducer. This is accomplished by connecting these respective switches in series with the corresponding one of the switches 2M1 through 2M4.

For example, the contact 12c of the switch S12 is connected in parallel with the contacts 32c and 42c of the switches S32 and S42, respectively, all of these contacts being connected to the remaining contact of the switch 2M2 of the auxiliary control switch. Hence, for example, upon the operation of push button S12, a circuit is completed from conductor 1 to the power supply contact 12b, to the contact 12c of the switch S12, to the contacts 2M2. From the common terminal of these contacts, the circuit continues through the motor 2M to the conductor 2 which completes the energizing circuit for the motor. Operation of the motor continues the rotation of the cam 20, until the cam projection opens the contacts 2M2, at which time the motor circuit is broken and the motor 2M is stopped.

As illustrated, the motor 2M drives the selector switch SS as well as the auxiliary control switch ACS. The selector switch SS is comprised of two separate switch sections, one of which includes the separate contacts SS1 through SS4, and the other of which includes an incom-

plete annular or arcuate contact 25, having a projection 26 thereon for engaging a stationary contact designated SSA. This stationary contact is electrically connected to the movable switch element 27, both elements being supplied with power through a circuit including conductor 27A, which will be described hereinafter. By means of parallel contacts which engage the arcuate contact 25, each of the contacts SS1 through SS4 is connected therewith. The movable switch element 27 and the arcuate contact 25 are both mechanically engaged to the motor 2M, to be driven thereby, and these elements are indexed with respect to the cam 20. Upon stopping of the cam 20 in a position opening any one of the motor control contacts 2M1 through 2M4, as for example the contact 2M3 which is shown open, the corresponding contact of the selector switch assembly SS is closed. In the illustrated case the contact SS3 of the selector switch is shown engaged by the movable switch element 27 thereof. In this position of the cam 20 the opening 25a in arcuate contact 25 straddles the stationary contact associated therewith corresponding to contact SS3. Thus this contact is effectively disconnected from the arcuate contact 25. Similarly, when the cam 20 occupies any of the three remaining positions in which contacts SS1, SS2, and SS4 are engaged, opening 25a straddles the corresponding contact associated therewith and therefore the arcuate contact is effectively disconnected from the circuit in each of the four single station positions of the cam 20. In the all station position of cam 20 switch 2MA is opened on switch ACS. Movable contact 27 now lies between contacts SS1 and SS4 and projection 26 engages contact SSA connecting the arcuate contact to circuit 27A. In this intermediate angular position of cam 20 the angular position of the arcuate contact is such that all four stationary contacts associated therewith are engaged thereby to thus connect all of the contacts SS1 through SS4 to conductor 27A.

The various contacts SS1 through SS4 of the selector switch SS are severally connected with certain corresponding contacts of switches C1 through C4 of the master switch unit MSS. The contacts of each master switch unit C1—C4 comprise a transfer contact assembly having a normally closed back contact and a normally open front contact. For example, the contact SS1 is connected with one of the two back contacts of the switch C1. The contact SS2 is connected with one of the two back contacts of the switch C2. The contact SS3 is connected with one of the two back contacts of the switch C3, and the contact SS4 is connected with one of the two back contacts of the switch C4. The other back contact of each switch C1—C4 is connected to the corresponding front contact, and these commonly connected contacts are respectively connected to the corresponding transducers T1—T4. For example, transducer T1 is connected with the common front-back contacts of the contact assembly C1, and the transducer T2 is connected with the common front-back contacts of switch C2, etc.

It will be understood that each switch C1—C4 includes a pair of front contacts and a pair of back contacts, and that one front contact and one back contact of each of said switches are connected together, and as thus electrically paired are connected to the transducers T1 to T4, respectively. As already noted, the back contacts of the switches C1—C4 which are not connected in

common to the respective transducers T₁—T₄ are connected severally to the contacts SS₁—SS₄, respectively, of the selector switch SS. The front contacts of the switches C₁—C₄ which are not connected in common to the respective transducers T₁—T₄ are connected in common to the conductor CA leading to a reversing switch of the double-pole, double-throw type actuated by a relay R.

The circuit designated 27A, which energizes the movable element 27 and the stationary contact SSA of the selector switch SS, is also connected to the double-pole, double-throw reversing switch, and the circuits CA and 27A are connected together through an amplifier generally designated A, having the input and output circuits designated I and O, respectively, which are also connected to the reversing switch.

The reversing switch is shown in its normal or deenergized position. This switch includes two contact arms R₁ and R₂, each arranged with two sets of transfer contacts. The back contacts of each set of transfer contacts are normally closed as shown, and, upon energization of the coil of the relay R, these contacts are opened and the front contacts thereof are closed. In the illustrated position of the reversing switch, the conductor CA is connected through the back contacts of the transfer contact assembly R₂ to the output circuit O of the amplifier, and the conductor 27A is connected through the back contacts to the transfer contact assembly R₁ to the input circuit I of the amplifier. These connections as will be hereinafter described connect the transducer at the station initiating a call with the output O of the amplifier and connect the called station or stations to the input of the amplifier. Thus to transmit a message from the calling to the called station the relay R must be operated from the calling station. Suitable switching means yet to be described is provided for this purpose at each station. While this mode of operation may be preferred for one application, in other applications the reverse may prove more convenient in which case the conductor CA will normally be connected to the input of the amplifier A and the conductor 27A connected to the output. This will connect the calling station to the input I and the called station to the output O. This, in practice, is accomplished by simply reversing the circuits I and O from that indicated. Switching means at the respective stations will again be provided to control relay R.

Assuming now that it is desired to connect the transducer T₁ with the transducers T₃, the push button switch assembly S13 of station S₁ is depressed, connecting the contacts 13A and 13C with the energizing contact 13B. A circuit is therefore completed for energizing the motor IM which is traceable from the supply conductor 1 to contact 13B, to contact 13A, to the motor control contacts of switch IM1. Assuming for the moment that the contacts of switch IM1 are closed, the motor-energizing circuit is completed through these contacts and the motor IM to the conductor 2. The motor is therefore operated until the projection 11 on cam 10 opens the switch IM1, at which time the motor circuit is interrupted and the motor stops. If the cam should be positioned as illustrated in the drawing at the time switch S13 is closed, the motor IM is not energized, nor need it be.

A circuit for operating the motor 2M is also established through switch S13 from supply conductor 1 to energizing contact 13B, to con-

tact 13C, to the contacts of switch 2M3 of the auxiliary control switch ACS. The switch 2M3 is incidentally shown in the open position required for the typical operation now under consideration. However, if the switch SM3 were closed (rather than in the position in which it is shown), a circuit would be established through the motor 2M to the supply conductor 2, thereby energizing such motor, and rotating the cam 20 until the contacts of switch 2M3 were opened and the motor de-energized. In view of the proper indexing and the common rotation of the movable switch element 27 with respect to the cam 20, such switch element engages the contact SS3 of the selector switch SS when the motor 2M stops, and thereby completes a circuit connecting the transducer T₁ with the transducer T₃. This circuit extends from the transducer T₁ through the conductor T₁A to the commonly connected front and back contacts of the transfer switch C₁. The closing of the push-button switch S13 having moved the cam 10 into the position shown in the drawing, the front contacts of the transfer contact assembly C₁ are closed and a circuit is established through these front contacts to the conductor CA connected thereto. From the conductor CA the circuit is connected to the output circuit O of the amplifier A through the back contacts of the transfer switch or contact assembly R₂. From the output circuit I of the amplifier the circuit continues through the closed back contacts of the transfer switch or contact assembly R₁ to the conductor 27A, which is engaged by rotary arm 27 to the contact SS3 of the selector switch SS. From contact SS3 the circuit extends through the closed back contacts of the transfer contact assembly or switch C₃ of master switch MSS, the commonly connected front and back contacts of which are connected to the transducer T₃.

Thus, by the provision of the individual master and auxiliary selector switch assemblies MSS and ACS, the manipulation of the contact S13 automatically and quickly interconnects the selected transducers T₁ and T₃. In this circuit connection, the transducer T₁ is connected to the output circuit of the amplifier A and the transducer T₃ is connected to the input circuit I of the amplifier. This circuit connection together with a selective switching control for the relay R (at each station) provides means whereby the operator at station S₁ may convey a message through the transducer T₁ to the transducer T₃ without any necessity of the party at the transducer T₃ taking any action.

The selective switching control at station S₁ is a push button operated talk-listen switch designated S1T, provided to control the energization of the relay R. Depression of the push button switch S1T energizes the coil of the relay R in a circuit which is traceable from the supply conductor 1 through the closed contacts of push button switch S1T to the conductor TC, which is connected with the coil of relay R, and the circuit is completed through the coil of relay R to the supply conductor 2. This relay therefore picks up and closes the front contacts of the respective transfer contacts R₁ and R₂, connecting the circuit CA with the input circuit I and the circuit 27A with the output circuit O, which operation, it will be appreciated, reverses the connection of the transducers T₁ and T₃ to the amplifier A, making it possible for the party at station S₁ to converse with party at station S₃.

All of the remaining switch stations are provided with corresponding talk-listen push buttons which are designated S2T, S3T and S4T, respectively. Each of these are connected to the conductor TC and are therefore in parallel with one another and in series with the coil of the relay R. Hence, operation of any one of these push buttons will energize the relay, thus affording selective control of the reversing switch from any one of the four stations illustrated.

Advantageously, I provide means for visually indicating the establishment of the circuits between any of the selected transducers T1—T4 upon operation of any selected push button, and also for indicating whether or not the system is busy. Such indicating means may be of any suitable form and in the illustrated embodiment lights are utilized to indicate these conditions.

More particularly, each station is provided with a busy light, respectively, designated BL1, BL2, BL3 and BL4, and each station is provided with a pilot light which indicates the establishment of the desired circuit. The pilot lights are designated PL1, PL2, PL3 and PL4, respectively. The control means for the busy light of each transducer is in the form of the switch, which again may be a push button switch, but preferably a switch which when closed will remain closed. These switches are respectively designated S1L, S2L, S3L and S4L. The busy lights BL1 through BL4 are connected in parallel with the conductors 2a and 2b, and any one of the switches S1L through S4L is adapted, when closed, to connect the conductor 2b to the supply conductor 1. Since the conductor 2a is connected to the supply conductor 2, it will be appreciated that the closing of any one of switches S1L through S4L establishes an energizing circuit for all of the busy lights across the supply conductors 1 and 2. Thus, the lights being on at the various stations indicate that the system is presently in use. The pilot lights PL1 through PL4 are so connected into the system that they are illuminated only at the station at which the operation is initiated, informing that part, when the light is illuminated, that the desired circuit is completed. Hence, returning to the illustration wherein the push button S13 is operated, as above described, the operator also closes the switch S1L, illuminating all of the bush lights BL1—BL4, and at the same time establishing a partial connection for energizing the pilot light PL1.

The pilot lights are controlled by the switches L1 through L4 of the master selector switch MSS. These pilot light switches are severally located on the individual contact stacks of the master selector switch, and are therefore selectively operated with the respective switch stacks. One contact of each switch L1—L4 is connected to the supply conductor 2, and the other contact of each of the light control switches is connected in series with the corresponding pilot light (PL1—PL4) and with the corresponding switch (S1L—S4L). Thus, the pressing of the push button S13 and the closing of switch S1L is effective through the operation of cam 10 to move the switch stack 1M1, C1 and L1 into the position shown, which, in addition to interconnecting transducers T1 and T3 as already described, completes the energizing circuit for the pilot light PL1 of station S1, said circuit extending from supply conductor 1 through switch S1L, through pilot light PL1 and through the switch L1 to supply conductor 2.

While the light system is desirable for the

reasons alluded to, it will be understood that there may be certain installations in which the light system may not be required.

When it is desired to connect the transducer T1 with all of the remaining transducers T2—T4 of the system, the push button S11 is depressed, thereby establishing an energizing circuit for the motor 1M through the contacts 1M1 of the master selector switch MSS as hereinabove traced, which circuit is interrupted when the cam 10 occupies the position illustrated. At the same time a circuit for energizing the motor 2M is completed from supply conductor 1 through the contacts 11b, 11c and conductor C to the junction point JA, and thence through the contacts of switch 2MA of the auxiliary control switch ACS and through the motor 2M to supply conductor 2. Motor 2M therefore rotates cam 20 until the contacts 2MA are opened and the operation of the motor interrupted.

With the cam 20 and switch elements thus positioned, the rotary switch arm 27 is located between the contacts SS1 and SS4 of the selector switch. However, the projection 26 on the annular contact 25, which is electrically united to all of the contacts SS1 through SS4, at this time engages the stationary contact SSA, wherefore all of the terminals SS1 through SS4 are connected with the back contacts of the transfer switches C2, C3 and C4 of the master selector switch MSS, while the switch C1 stands removed from its back contacts. The switches C2, C3 and C4, as thus closed across their back contacts, complete the circuits to the respective transducers T2, T3 and T4. While the back contacts of the switch C1 stand open, as shown, the front contacts of this switch are closed, thereby connecting transducer T1 to transducers T2, T3 and T4, the connection from the closed front contacts of switch C1 of transducer T1 extending through line CA, switch R2, amplifier A, switch R1, line 27A, contact SSA, engaged by projection 26 on ring 25, and the conductors leading from said ring through the closed back contacts of switches C2, C3 and C4 to the said transducers T2, T3 and T4.

The manipulation of the talk-listen switch S1T at station S1 provides reversible communication between station S1 and all of stations S2, S3 and S4. As in the case wherein transducer T1 was connected with the transducer T3, the transducer T1 is again connected to the output circuit of the amplifier A, while the remaining transducers are connected to the input circuit thereof. Although the amplifier circuit will normally be reversed by operation of the switch S1T at station S1, this circuit may also be reversed by operation of any of the parallel connected switches S2T, S3T and S4T in the remaining switch stations.

While the operation of the system has been described part by part with the development of the description of the various components, a better understanding of the invention may be had from a brief résumé of the operation of the system as a whole. For convenience in this description, it will again be assumed that the transducer T1 is desired to be connected with the transducer T3. In operating the system the operator at station S1 first depresses the light switch S1L to illuminate the busy lights BL1 through BL4. Thereafter the push button S13 is depressed and held down for an interval slightly longer than that required to illuminate

the pilot light PL1. With the depression of push button S13, the motor 1M operates until the contacts 1M1 of the master selector switch MSS are opened, which also opens the back contacts of the transfer switch C1 and closes the front contacts thereof, and at the same time closes the contacts L1, which effects the illumination of the pilot light PL1. The closing of the switch C1 connects the transducer T1 through the then closed front contacts of the transfer contact switch C1 to the conductor CA which is connected to the output circuit of the amplifier A. The energizing circuit closed from supply line 1 through contacts 13b and 13c to the contacts 2M3 of the auxiliary control switch ACS energizes the motor 2M, which stops when the cam 20 opens the contacts 2M3. In this position of the cam the rotary switch arm 27 engages contact SS3, and thereby completes an energizing circuit leading from the input circuit I of the amplifier A, relay switch R1, line 27A and arm 27 to the closed back contacts of the transfer switch C3, and thence to the transducer T3, completing the desired circuit between the two transducers T1 and T3.

From the foregoing it will be appreciated that any one of the transducers T1-T4 may be connected with any one of the remaining transducers by simply manipulating a selected push button on the corresponding station to effect the desired connection. Likewise any one transducer may be connected to all of the remaining transducers by operating the proper push button on that particular station.

It will be appreciated that the equipment at the respective stations S1-S4 is both simple and inexpensive, including merely a transducer which may comprise a permanent magnet speaker commonly used for this purpose, and a push-button assembly having a push-button for each station of the system, together with a talk-listen push-button, and an indicating light switch, if desired. Elements such as these are inexpensive and are easily and conveniently arranged in an attractive and compact unit.

The remaining components of the system are also relatively simple and easily manufactured. These components, for example the master switch MMS, the auxiliary selector switch SS, the auxiliary control switch ACS, and the electric motors 1M and 2M therefor may be conveniently assembled on a single base. The entire arrangement is small in dimension, which may, together with the single amplifier A be disposed at a convenient point in the system, where the various stations may be easily wired and available for service.

With these few components it should be noted each station of the system is a master station, where a person may converse at will with any one or with all of the other stations, without the need for personnel at any of the other stations to take part in the establishment of the circuits, or in the operation of the system for two-way communication. Thus, it will be appreciated that in addition to the simplicity of the equipment, the equipment is highly flexible and at the same time very easily operated.

While cam-operated switches have been herein indicated for performing the various switching functions, it will be appreciated by those skilled in the art that relay circuits may be readily substituted therefor. The present arrangement in many instances will be preferred, since the cost of equipment of the type herein

shown is a great deal less than that of relay equipment. Furthermore, the unit assembly of the switches is relatively compact.

The indicating light system may be elaborated, if desired, by connecting the lights respectively in a circuit including in series therein, in addition to the respective switches L1 through L4, a corresponding set of switches on the auxiliary control switch ACS, each of which would be connected in series with its corresponding switch L1 through L4, the circuit being completed to the conductor 2 in exactly the same manner as the present circuit for the switches L1 and L4. With such an arrangement all of the series switches would of necessity be closed prior to the time the pilot lights of the respective stations would be illuminated.

While a preferred embodiment of this invention has been illustrated and described, it will be appreciated by those skilled in the art that numerous changes in the circuit and its components, and in the arrangement of these circuit components, may be made without departing from the spirit of the invention defined in the appended claims.

I claim:

1. An intercommunication system comprising a switching network for connecting together a plurality of electrical transducers comprising in combination, a switch station for each transducer, each switch station comprising a switch for each station; each switch having a first normally open contact and a second normally open contact, circuit means connecting said first contacts of each switch station in parallel, circuit means connecting the corresponding second contacts of the separate switch stations in parallel, a master switch unit for each station; an auxiliary switch unit for each station; master switch control circuit means connecting each master switch unit with the paralleled first contacts of the corresponding switch station, auxiliary switch control circuit means connecting each auxiliary switch unit with the corresponding paralleled second contacts, circuit means connecting each transducer with the corresponding master switch unit, and circuit means connecting the corresponding auxiliary switch units and master switch units.

2. An intercommunication system comprising a switching network for connecting together a plurality of electrical transducers comprising in combination a switch station for each transducer, each switch station comprising a switch for each station; each switch having a first normally open contact and a second normally open contact, each switch representing at least one station other than the station at which it is located, circuit means connecting said first contacts of each switch station in parallel, circuit means connecting the corresponding second contacts of the several switch stations in parallel, and circuit means responsive to operation of any particular switch of a given station for connecting the transducer of said given station to the transducer of the station represented by said particular switch.

3. An intercommunication system comprising a plurality of transducers, a master switch unit for each transducer, an auxiliary switch unit for each transducer, circuit means connecting each transducer to the corresponding master switch unit, circuit means connected in common with all the master switch units and all the auxiliary switch units, circuit means for individually connecting the master switch units to the corresponding auxiliary switch units, and circuit

13

means for simultaneously actuating a selected master switch unit and a selected auxiliary switch unit.

4. Apparatus as set forth in claim 3, in which said circuit means connected in common with all the master and auxiliary switch units comprises an amplifier having an input and an output circuit connected in series with each of the master switch units and each of the auxiliary switch units.

5. Apparatus as set forth in claim 3 in which said circuit means connected in common with all the master and auxiliary switch units comprises an amplifier having an input and an output circuit connected in series with each of the master switch units and each of the auxiliary switch units, a reversing switch for reversing the connection of said input circuit and output circuit, and a separate switch for each transducer for actuating said reversing switch.

6. An intercommunication system comprising a plurality of transducers, a master switch unit for each transducer, each master switch unit having a pair of normally open contacts and a pair of normally closed contacts, one normally open contact and one normally closed contact of each of said pairs of contacts in each master switch unit having a common terminal, circuit means connecting each transducer to said common terminal of the corresponding master switch unit, an auxiliary switch having a pair of contacts, electrical conductor means connecting all of the other normally open contacts of the several master switch units with one of said pair of contacts of said auxiliary switch, circuit means connecting all of the other normally closed contacts of the several master switch units with the other of said pair of contacts of said auxiliary switch, and circuit means for simultaneously actuating a selected one of said master switch units and said auxiliary switch.

7. Apparatus as set forth in claim 6, in which said electrical conductor means includes an amplifier.

8. Apparatus as set forth in claim 6, in which said electrical conductor means includes an amplifier having an input circuit and an output circuit, said input circuit being connected with all said other terminals of said normally open contacts and said output circuit being connected to said one contact of said pair of contacts of said auxiliary switch, and a reversing switch connected with said input circuit and said output circuit for reversing the connection of said input and output circuits.

9. An intercommunication system comprising a plurality of transducers, a master switch unit for each transducer, each master switch unit including a pair of normally open contacts and a pair of normally closed contacts, one normally open and one normally closed contact of each pair of said contacts having a common terminal, an auxiliary control switch assembly including an auxiliary switch for each transducer, each auxiliary switch having a pair of contacts for each transducer, each auxiliary switch having one contact of each pair of contacts connected in common, a selector switch connected to operate in synchronism with said auxiliary control switch assembly, circuit means connecting the transducers respectively to said common terminals of said master switch units, control circuit means connecting each of the other contacts of said auxiliary switches respectively to the other of said normally closed contacts of said master switch

14

units, circuit means connecting the other contact of said selector switch with each of said other contacts of said auxiliary switches of the auxiliary control switch assembly, and circuit means for simultaneously operating a selected master switch unit and an auxiliary switch of said auxiliary control switch assembly.

10. Apparatus as set forth in claim 9, in which said control circuit means includes an amplifier.

11. Apparatus as set forth in claim 9, in which said control means includes an amplifier having an input circuit and an output circuit, and a reversing switch normally connecting said input circuit to the other contacts of said normally open contacts of said master switch units, and means electrically connecting said output circuit to the common-connected contacts of said auxiliary switches and to a contact of said selector switch.

12. Apparatus as set forth in claim 9, a cam for actuating the master switch units, a motor for driving said cam, switch means on each master switch unit for controlling said motor, and control circuit means selectively connecting each of said switch means and said motor in series.

13. A pilot light circuit for an intercommunication system comprising the combination of a plurality of transducers, a master selector switch having a plurality of master switch units severally connected to said transducers, an auxiliary control switch assembly having an auxiliary switch unit for each transducer connected with a corresponding master switch unit, a switch station for each transducer including a switch for each transducer, all the switches of each switch station being connected with the corresponding master switch unit and the corresponding switches of each station being connected with the corresponding auxiliary switch units, a pilot light for each transducer, a pilot light switch in each switch station, and circuit means connecting each pilot light in series with the corresponding pilot light switch and the corresponding master switch unit.

14. Apparatus as set forth in claim 13, and a busy-signal light for each transducer, and circuit means connecting each of the busy-signal lights in series with said pilot light switch.

15. In an intercommunication system, the combination of a plurality of transducers, a motor operated master switch unit for each transducer, a motor operated auxiliary switch unit for each transducer, circuit means connecting the corresponding auxiliary switch and master switch units, circuit means connecting each transducer with the corresponding master switch unit, and switching means for each transducer for controlling the motor operated master switch unit for controlling the motor operated auxiliary switch unit.

16. In an intercommunication system, the combination of a plurality of speaker-microphone stations each having individual switch units corresponding in number to the number of said stations, a master switch assembly comprising a plurality of master switch units corresponding in number of the number of said stations, an auxiliary switch unit comprising a plurality of auxiliary switch units corresponding in number to the number of said stations, circuit means responsive to operation of any one switch on one of said stations for operating the corresponding master switch unit, circuit means responsive to operation of any one of the corresponding switches on the different stations for

operating the corresponding auxiliary switch unit, circuit means connecting each speaker-microphone unit with the corresponding master switch unit, and circuit means connecting each auxiliary switch unit with the corresponding master switch unit.

17. In an intercommunication system for selectively connecting together a plurality of electrical devices, the combination of a switch station for each device having individual switch units corresponding in number to the number of devices, a master switch assembly having a plurality of master switch units corresponding in number to the number of switch stations, an auxiliary switch assembly having a plurality of auxiliary switch units corresponding in number to the number of said switch stations, circuit means responsive to operation of any one switch of one of said stations for operating the corresponding master switch unit, circuit means responsive to operation of any one of the corresponding switches of the different switch stations for operating the corresponding auxiliary switch unit, circuit means connecting each electrical device with the corresponding master switch unit, and circuit means connecting each auxiliary switch unit with the corresponding master switch unit.

18. In an intercommunication system for selectively connecting together a plurality of electrical transducers, the combination of a switch station for each transducer having an individual switch unit for each transducer, a master switch assembly having a master switch for each transducer, each master switch unit having a normally open contact and a normally closed contact, an auxiliary switch assembly having an auxiliary switch unit for each transducer, a common circuit for each normally open contact of the master switch units, a common circuit for the auxiliary switch units, circuit means connecting said common circuits together, circuit means connecting each transducer to the corresponding normally open and normally closed contacts of the master switch units, circuit means connecting each auxiliary switch unit with the corresponding normally closed contact of each master switch unit, circuit means connected with each switch station and responsive to operation of any one switch of one of said stations for operating the corresponding master switch unit, and circuit means responsive to operation of any one of the corresponding switches of the different switch stations for operating the corresponding auxiliary switch unit.

19. In an intercommunication system for selectively connecting together a plurality of electrical transducers, the combination of a switch station for each transducer, each switch station comprising one switch for each station, each switch having a pair of normally open contacts, a master switch unit for each switch station, an auxil-

iary switch unit for each station, circuit means connecting the corresponding contacts on the several switch stations in parallel, circuit means connecting the remaining contact of each switch in parallel with corresponding remaining contacts of the switches on the other switch stations, control circuit means for each master switch unit connected with the paralleled contacts of corresponding switch stations, control circuit means for each auxiliary switch unit connected with the corresponding paralleled remaining contacts of the separate switch units, circuit means connecting the corresponding master switch units and auxiliary switch units together, and circuit means connecting each transducer with the corresponding master switch unit.

20. In an intercommunication system, the combination of a plurality of stations each including a speaker-microphone and a push-button control having push-buttons corresponding in number to the number of stations, a pair of contacts for each push-button, a master selector switch including a switch stack for each station, each switch stack having a normally closed contact and a normally open contact, an auxiliary selector switch including a switch stack for each station, an amplifier having an input circuit and an output circuit, means connecting each speaker-microphone with the normally open contact of the corresponding master switch stack, circuit means connecting each normally open contact of said master switch with one of the circuits of said amplifier, circuit means connecting each switch stack of said auxiliary switch with the other circuit of said amplifier, circuit means connecting each switch stack of said auxiliary switch in series with the corresponding normally closed contact of said master switch and with the corresponding speaker-microphone, actuating means for the master switch for selectively actuating the switch assemblies of the master switch in response to operation of any one push button on the respective push-button controls, and second actuating means for selectively actuating any one switch stack of said auxiliary switch in response to operation of corresponding push-buttons of the respective push-button controls.
